UNITED STATES PATENT OFFICE

FELIX LONG, OF NEW CITY, NEW YORK

PICTURE FRAME

Application filed March 13, 1931. Serial No. 522,290.

This invention relates to the framing and hanging of pictures. Heretofore it has been the universal practice in the framing of pictures to employ a rabbeted frame in which the 5 glass, picture and a suitable backing are successively placed and the backing is thereupon secured in position by driving small brads or nails into the frame, so as to overlie the backing and preclude its inadvertent displacement. To preclude the entrance of dust about the edges of the backing, it has been the practice to paste paper over the back of the frame. Considerable skill is required in the framing of pictures in this manner and if it 10 is desired to change the picture in the frame at any time, tools are required and skill is needed to make the change.

The primary object of the present invention is to provide a greatly simplified mode of 20 procedure and one which will permit of an expeditious substitution of a picture in a frame without requiring tools, and without necessitating any skill.

A further object of the invention is to so 25 constitute the picture framing means that it will serve not only to maintain the picture in position, but will also form a dust-tight seal which will eliminate the necessity of pasting paper over the back of the frame.

30 Another object of the invention consists in the provision of novel and efficient means for suspending a frame from a picture hook or other suitable support in such manner as to permit the hanging of a picture at any desired angle as well as a change of such angle when desired.

An important feature of the invention resides in the novel interaction between the framing and suspending means whereby the 40 framing means serves as a firm anchorage for the suspension means and carries the weight of the frame and glass in a manner to preclude inadvertent breakage or release of the frame when suspended as stated.

45 The present invention is particularly characterized by the fact that instead of maintaining the glass, picture and backing in place by brads or nails as heretofore, these parts are held in position by retaining strips 50 which are in turn held against inadvertent

displacement in a position to hold the parts in place by means of retainers which are mounted permanently upon the frame and engage with the retaining strips in such manner as to hold them firmly in position.

The invention may partake of various practical forms, but in one of its commercial embodiments, it comprises a frame at the four corners of which the retainers are positioned. These retainers in this embodiment of the invention constitute pockets which serve not only to reinforce the frame at its corners, but also provide for the introduction into said pockets of the ends of the retaining strips, so that after the glass, picture and backing have been positioned in the frame, the retaining strips may be brought into position with their opposite ends in the pockets as stated for the purpose of maintaining the integrity of the assembly and preclude inadvertent disengagement of any of the parts from the frame.

The suspension means in the preferred practical form of the invention is mounted on and secured to the retainers and may be 75 thus firmly and securely anchored to the frame as will hereinafter be more fully described.

Features of the invention, other than those adverted to, will be apparent from the hereinafter detailed description and claims, when 80 read in conjunction with the accompanying drawings.

The accompanying drawings illustrate different practical embodiments of the invention, but the constructions therein shown are 85 to be understood as illustrative, only, and not as defining the limits of the invention.

Figure 1 is a back view of a picture frame made in accordance with the present invention.

Figure 2 is a section on the line 2-2 of Figure 1.

Figure 3 is a perspective view of one corner of the frame showing one of the retainers in phantom.

Figure 4 shows the retainer removed from the frame.

Figure 5 is a perspective view of a terminal member forming part of the picture suspending means.

Figure 6 shows a modified form of retainer.

Figure 7 shows a further modified form of retainer.

5 Referring to the drawings, 1 designates the picture frame which is constructed in the usual conventional manner, the frame being rabbeted at its back as shown best at 2 in Figures 2 and 3. In this rabbet the 10 glass 3, picture 4 and backing 5 are adapted to be superimposed, as shown in Figure 2, in the usual manner.

In the construction as illustrated in Figs. 15 1-5, inclusive, there is attached in the rabbets at each of the four corners of the frame an angular corner piece 6. Each of these corner pieces is in the form of an angle, across the top of which is a web 7, the free edge of which is provided with turned back or hook 20 tongues 8 and 9 as clearly shown in Figure 4. The angular portions of the corner pieces 6 extend beyond the web 7 in right angular relation to one another to form extensions 10 and these extensions are perforated at 11, 25 so that when the corner pieces are positioned in the corner of the rabbet, nails or screws may be passed through the perforations 11 into the frame to permanently mount the corner pieces on the frame. As shown in 30 Fig. 3, these corner pieces preferably extend to the base of the rabbet 2, so that when the glass is positioned in the frame, the corner pieces will overlap the edges of the glass and thus bear upon and be supported by the corner pieces, when the frame is suspended as 35 hereinafter described. It will be noted moreover that the corner pieces will serve as a reinforce at the corners of the frame to maintain the frame square and at the same time preclude joints at the corners of the frame from opening after long periods of use.

The corner pieces 6 are secured in the rabbet as described after the glass has been put 45 into the frame, because it will be practically impossible to set the glass after these corner pieces are in place, but when the parts are assembled as stated, it will be noted that the said corner pieces form with the glass pockets at all four corners of the frame. The picture and the backing may be readily introduced into these pockets or removed therefrom by slightly bending the picture and backing, which are allowed to flatten out 50 again after being positioned in the frame. The backing will of course be positioned some little distance from the webs of the corner pieces and the space thus provided is availed of for the introduction of retaining strips, the purpose of which is to hold the backing and picture firmly against the glass. In the carrying out of this function, the corner pieces operate as retainers.

The retaining strips are indicated in the 55 drawings by the reference numerals 12, 13

and 14. There are four of these strips and they may be conveniently made from wood, metal, heavy cardboard or any other suitable material having sufficient rigidity so as not to materially bend longitudinally.

The strip 13 is of a length to fit across the top of the frame with its ends abutting the shoulders of the rabbet at the sides of the frame. This strip is the first to be inserted beneath the retainers 6 at the top of the 70 frame. The strips 12 are next brought into position as indicated by the arrow 12a and they are of such length that when their upper ends abut the strip 13 beneath the upper retainer, their lower ends will abut the shoulder of the rabbet at the bottom of the frame beneath the lower retainers. Lastly the strip 14 is brought into position between the lower ends of the strips 12 and beneath the corresponding retainers and serves as a 75 key to hold all of the strips in place. In practice, the strips should be cut to such size or fitted that they will not inadvertently work loose. Small prongs or spurs or tenons may be provided at the ends of the 80 strips to dig or fit into the frame or into one another to more positively secure them in position, but in practice this is unnecessary. The thickness of the strips is such that when forced into position as shown, they 85 will press the backing firmly against the picture and thus hold it in contact with the glass throughout.

It will of course be understood that with the arrangement described, the picture and 90 backing may be readily placed in the frame and the retaining strips thereupon introduced by wholly inexperienced persons without the use of any tools and in a simple and expeditious manner and a later substitution 95 of pictures in the frame can be accomplished with equal ease and celerity.

As I have hereinbefore noted, the strips are adapted to fit tightly within the frame and will thus tend to place some little stress upon the retainers at the corners of the frame, but the mounting of the retainers in the corners of the frame thoroughly reinforce the frame and the actual stresses are transmitted from the retainers directly to the sides of the frame and therefore will not have any tendency to open up the corners. These stresses are, moreover, exerted in an outward direction which, as will hereinafter be fully explained, is contra or opposite to the stresses 110 imposed upon the retainers by the suspension means.

It will be understood that the invention, as thus far described may be employed with any suitable suspension means, but the structure 115 lends itself to a novel and highly efficient form of suspension means which will now be described.

As hereinbefore stated, the web 7 of each of the corner pieces 6 is provided with hook 120

flanges 8 and 9. These hook flanges relate to the suspension of a picture. Heretofore it has been the customary practice to suspend pictures by securing screw eyes in the back 5 of the frame and attaching the picture wire directly thereto. In accordance with the preferred form of this invention, in contradistinction, the picture wire is secured to the corner pieces as shown best in Figure 1. A 10 picture wire 16 of suitable length is provided at both of its ends with terminal members of any suitable type, e. g., such as shown in Figure 5. Each of these terminal members is in the form of a flat strip 17 having 15 along one of its edges turned back or hook flanges 17, 18, 19 and 20. One end of the wire is led in the trough beneath these flanges as shown at 21. It is then carried along the trough to the right in Fig. 5 and over the end 20 of the flange 20, thence along the front of the flange as indicated at 22, thence behind the flanges 19, 18 and 17 to the opposite end of the member. It is then bent about the opposite end of said member and returned over 25 its outer face after which it is passed back of the flange 18 and brought out between the flanges 18 and 19. The wire is thus turned back and forth upon itself over and under the flanges as stated, so as to firmly anchor each 30 end of the wire to the corresponding terminal member. To attach the wire to the frame, the terminal members at the opposite ends of the wire 16 are positioned behind the hook flanges 8 and 9 of the upper corner pieces 35 with the wire extending out through the space between these flanges. This constitutes a firm anchorage for the opposite ends of the wire. The wire is then led downwardly along the sides of the frame and behind the hook flange 9 at each lower corner, thence carried along beyond the flange 9 and over the flange 8 to the opposite end of said flange. It is then looped behind the flange 8 and brought out at the same edge of the flange 9 45 as it enters, but for the purpose of a clear showing in the drawings, it is illustrated as coming out between the flanges 8 and 9.

The adjustors 23 are in the form of slides which preferably embody two converging 50 passages. That portion of the wire which extends between the corner pieces extends through one passage and that portion of the wire which extends from the lower corner pieces upwardly to the adjusting member 55 extends through the other passage. The upwardly converging form of the passages will, I have found, slightly distort the wire by changing its direction in such manner that when the slides are manually moved up and 60 down, they will retain the position in which they are left and will not inadvertently change position. It will thus appear that those portions of the wire which extend between the upper and lower corner pieces 65 form guides for the vertical adjustment of

the slides 23 and serve in effect as a harness from which the frame is supported on the remaining portion of the wire. From the slides 23, the wire extends upwardly and is looped over the picture hook or other suitable 70 support. By moving the slides up or down, the frame may be caused to hang at such angle as may be desired.

In the foregoing description, I have referred to the corner pieces or retainers as 75 mounted in a rabbet and they are thus shown in Fig. 3. It is within the purview of this invention, however, to mount the corner pieces or retainers exteriorly of the frame, so as to overlap the outer edges at the corners. 80 Such an arrangement is shown in Fig. 6, wherein the corner pieces are designated at 6a and secured in place by nails or screws passed through perforations 11a into the frame. Furthermore, while the utilization of 85 retainers to function as corner pieces for the purpose of reinforcing the frame is desirable, I have found that the use of retaining strips in framing as described may be carried out by the use of retainers 6b, such as shown in 90 Fig. 7. These retainers are in the form of plates fastened to the back of the frame by nails or screws 11b and so shaped in proportion as to extend over the rabbets to engage 95 with and hold in place the retaining strips 12 and 14. It thus appears that the retainers 100 constitute in effect devices mounted upon the frame and extending over the strips 12 and 14 to hold them in position and from what has been said it would appear that these extensions may engage with the strips either at their ends as shown in Figs. 1 and 6, or intermediate the ends of these strips as shown in Fig. 7.

In the foregoing detailed description and in the appended claims, I have specifically referred to the framing of pictures which, in accordance with the usual practice, involves the use of glass, the picture to be framed and a suitable backing. I wish it to be understood, however, that in showing and describing this invention, I have done so for the purpose of illustration, only, and that, in practice, I may frame documents, tiles, 105 mirrors and various other articles, papers, 110 cardboards or fabrics without departing from this invention. Certain of such articles will require a glass and a suitable backing. With others, for example tiles, neither glass nor a 115 backing will be necessary. In view of these facts, I wish it clearly understood that in the appended claims wherein glass, a picture and a backing are referred to, that these elements are to be considered as equivalents of a mirror, a tile or other appropriate matter 120 which is to be framed through the employment of a recessed frame with retaining strips as hereinbefore described as forming the fundamental feature of this invention.

In the accompanying drawings, I have 125 130

shown retainers of various forms, but it will be understood that these may vary in shape without departing from this invention.

Having thus fully described the invention, what I claim as new and desire to secure by Letters Patent is:

1. In an assembly of the character described, a rectangular picture frame rabbeted at its back to provide a recess adapted to receive a glass, a picture and a backing, retainers mounted on the frame and extending across the rabbet at the corners of the frame to form pockets and four strips respectively positioned in the rabbets at the four sides of the frame with the ends of the several strips extending into the corner pockets to hold the strips in position and thus maintain the glass, picture and backing against inadvertent displacement, each of said retainers having flanges secured to two adjacent sides of the frame to reinforce the frame at its corners.
2. In an assembly of the character described, a rectangular picture frame rabbeted at its back to provide a recess adapted to receive a glass, a picture and a backing, retainers mounted on the frame and extending across the rabbet at the corners of the frame to form pockets and four strips respectively positioned in the rabbets at the four sides of the frame with the ends of the several strips extending into the corner pockets to hold the strips in position and thus maintain the glass, picture and backing against inadvertent displacement, each of said retainers having flanges extending into and secured within the rabbet to reinforce the corners of the frame.
3. In an assembly of the character described, a rectangular picture frame rabbeted at its back to provide a recess adapted to receive a glass, a picture and a backing, retainers mounted on the frame and extending across the rabbet at the corners of the frame to form pockets and four strips respectively positioned in the rabbets at the four sides of the frame with the ends of the several strips extending into the corner pockets to hold the strips in position and thus maintain the glass, picture and backing against inadvertent displacement, each of said retainers having an angular flange positioned in the angle of the rabbet and secured to adjacent sides of the frame to mount the retainers on the frame and reinforce the corresponding corner thereof.
4. In an assembly of the character described, a rectangular picture frame rabbeted at its back to provide a recess adapted to receive a glass, a picture and a backing, retainers mounted on the frame and extending across the rabbet at the corners of the frame to form pockets and four strips respectively positioned in the rabbets at the four sides of the frame with the ends of the several strips extending into the corner pockets to hold the strips in position and thus maintain the glass, picture and backing against inadvertent displacement, each of said retainers having an angular flange positioned in the angle of the rabbet and secured to adjacent sides of the frame to mount the retainers on the frame and reinforce the corresponding corner thereof, said flanges extending to the base of the rabbet to embrace the corresponding corners of the backing, picture and glass.
5. In an assembly of the character described, a frame provided at the back thereof with a recess adapted to receive a glass, picture and a suitable backing, retainers mounted on the frame and extending over said recess in spaced relation to the backing, and retaining strips positioned in the recess between the backing and retainers to maintain the glass, picture and backing in position against inadvertent displacement from the frame, said retainers comprising plates secured to the back of the frame in spaced relation to the corners thereof.
6. In an assembly of the character described, a rectangular frame provided with a rabbet at the back of its inner edge, corner angles secured to the four corners of the frame to reinforce the same, each corner angle having a web overlying the rabbet at the corresponding corner of the frame and each web being provided with a hooked flange, said webs forming pockets between the base of the rabbet and the webs at the several corners of the frame, retaining strips positioned in the rabbet at the four sides of the frame with the opposite ends of the several strips extending into said pockets, a suspension member provided at its opposite ends with terminal members, said terminal members being engaged with the hook flanges at the upper corners of the frame and from thence extended downwardly along the sides of the frame and loop about the hook flanges at the bottom of the frame and thence extended upwardly in the form of a suspension loop, and slides embracing both of said downwardly and upwardly extending portions of the suspension member at the opposite sides of the frame and vertically adjustable to regulate the angle at which the frame will hang.
7. In a picture frame having rabbets at the back to receive a glass, a picture and a backing, a plurality of relatively rigid strips engaging the backing adjacent to its edges; and a plurality of retaining members mounted on the back of the frame overlapping the rabbets and frictionally engaging the strips to hold the parts assembled and so arranged as to permit quick removal of the strips.
8. An assembly of the character described comprising a rectangular frame having rabbets at the back to receive matter to be displayed and a backing; a plurality of

flat retaining strips on the backing overlying the rabbets and having their outer faces substantially flush with the back of the frame; and clamping members on the back of the frame extending transversely of the rabbets frictionally engaging the strips to hold the parts assembled in the frame.

9. An assembly of the character described comprising a rectangular frame having rabbets at the back to receive matter to be displayed and a backing; a plurality of flat retaining strips on the edges of the backing and abutting the outer edges of the rabbets; spaced retaining members secured to the back of the frame and projecting transversely of and frictionally engaging the strips to hold them assembled in the frame and clamp the parts in the rabbets.

In testimony whereof I have signed the foregoing specification.

FELIX LONG.
